UNITED STATES PATENT OFFICE

93,674

DESIGN FOR A COASTER WAGON

John G. Rideout, Perrysburg, Ohio, assignor to
The American-National Company, Toledo,
Ohio, a corporation of Ohio

Application August 9, 1934, Serial No. 52,876

Term of patent 7 years

To all whom it may concern:

Be it known that I, JOHN G. RIDEOUT, a citizen of the United States, and resident of Perrysburg, in the county of Wood, State of Ohio, have invented a new, original, and ornamental Design for a Coaster Wagon, of which the following is a specification, reference being had to the accompanying drawing, forming a part thereof.

Figure 1 is a front and side perspective view; Fig. 2 is a rear and side perspective view, and Fig. 3 is a front perspective view of a coaster wagon showing my new design. The dominant features of my design consist in the drop skirt effect, whereby the wheels are partially enclosed; the upwardly and rearwardly rounded nose portion which is of curve-form in cross-section with

its side edges merging in a curved line into the forward ends of the side skirt portion of the body sides; the provision of upwardly extending recesses between the lower side edges of the nose portion and the forward lower end edges of the side skirt portions to expose the front wheels in a front end view of the wagon, and the curved rearwardly and downwardly extending rear end of the body, which is substantially straight across.

I claim:

The ornamental design for a coaster wagon, substantially as shown and described.

In testimony whereof I have hereunto signed my name to this specification.

JOHN G. RIDEOUT.
